Primary Examiner — Jeffrey D Asch*Assistant Examiner* — Rebekah A Caruso(74) *Attorney, Agent, or Firm* — Charles S. Sara; DeWitt LLP(57) **CLAIM**

The ornamental design for a surgical retractor, as shown and described.

DESCRIPTION

FIG. 1 is a front, bottom perspective view of the surgical retractor showing my design;

FIG. 2 is a front, top perspective view thereof.

FIG. 3 is a front elevational view, the rear elevational view being a mirror image.

FIG. 4 is a left side elevational view, the right side elevational view being a mirror image.

FIG. 5 is a top plan view thereof; and,

FIG. 6 is a bottom plan view thereof.

The hatch lines of the figures are shading lines and do not form a part of the invention.
